UNITED STATES PATENT OFFICE.

CLAUDE T. WOMACK, OF PHOENIX CITY, ALABAMA, ASSIGNOR OF ONE-HALF TO
HARRY O. DAVIDSON, OF COLUMBUS, GEORGIA.

TRANSFER MECHANISM FOR REPLENISHING LOOMS.

1,258,074.

Specification of Letters Patent.

Patented Mar. 5, 1918.

Application filed June 25, 1917. Serial No. 176,857.

To all whom it may concern:

Be it known that I, CLAUDE T. WOMACK, a citizen of the United States, and a resident of Phoenix City, in the county of Lee 5 and State of Alabama, have invented certain new and useful Improvements in Transfer Mechanism for Replenishing Looms; and I do hereby declare the following to be a full, clear, and exact description of the 10 invention, such as will enable others skilled in the art to which it appertains to make and use the same.

This invention relates to improvements in filling replenishing looms and more particularly to the transfer devices therefor.

With prior constructions of transfer mechanism for filling replenishing looms, danger of breakage of the bobbins has occurred by reason of the tendency of the transfer finger 20 employed, to become distorted (as frequently happens) and result in splitting the bobbin in forcing the same from the magazine to the shuttle, and in some instances, breakage of the shuttle has been caused by engagement of the transfer finger therewith 25 on account of the bending of said finger.

An object of my present invention is to so construct transfer devices for filling replenishing looms, as to eliminate breakage of 30 the bobbins and shuttle and to obviate the danger to the operator, as heretofore encountered when a shuttle is broken with possibility of accident from broken pieces.

A further object is to construct the transfer devices in such manner that the cost of 35 loss from breakage of bobbins and shuttles shall be saved without materially increasing the cost of construction of said devices.

A further object is to so construct the transfer devices that the same shall be readily adjustable for bobbins of different 40 lengths.

With these and other objects in view, the invention consists in certain novel features 45 of construction and combinations of parts as hereinafter set forth and pointed out in the claims.

In the accompanying drawings; Figure 1 is a side elevation partly broken away illustrating the application of my invention; Fig. 2 is a plan view, partly in section, and Fig. 3 is an end elevation partly in section.

I represent a rotary magazine or carrier for filled bobbins 2,--the latter being held

normally in position therein by means of 55 springs 3. At the proper time, controlled by suitable mechanism well known in the art and not necessary to describe herein, a shuttle 4 will become properly positioned, as shown in Fig. 1, to have its depleted bobbin 5 ejected and to receive a filled bobbin 2 from the magazine. A filled bobbin 2 at this time will be directly over the shuttle.

An arm 6 is loosely mounted on a fixed shaft 7 and provided at its free end with a head 8 adapted to engage one end of the bobbin 2. The arm 6 is also provided at its free end with a laterally projecting, internally threaded boss 9 to receive one end portion of a threaded rod or stud 10, which latter is thus adjustably connected with the boss 9 and is retained in position by means of a nut 11.

The shank 12 of a transfer finger 13 is 75 perforated for the accommodation of the threaded rod or stud 10,—said finger being elongated in form and dished as at 14 to engage the body of the filled bobbin at an appreciable distance from the end thereof which is engaged by the head 8 on the arm 80 6. The shank 12 is disposed at right angles to one end of the finger 13 and is held at any desired adjustment on the rod or stud 10 by means of nuts 15, 15. Thus it will be seen that the transfer finger may be readily adjusted for bobbins of different lengths, that it does not engage the mechanical structure 85 of the bobbin *per se*, and that it can never strike the shuttle during the transfer of a bobbin thereto from the magazine.

Normally, the transfer device is kept out of contact with the filled bobbin by means of a spring 16 coiled on the hub of arm 6 and attached at one end to a collar 17 fixed to the shaft 7, the other end of said spring engaging the arm 6.

When a shuttle is in position to receive a filled bobbin from the magazine, the arm 6 will be operated by suitable mechanism (not shown) to cause the head 8 and finger 13 to force a filled bobbin out of the magazine and into the shuttle, and at the same time the entrance of the filled bobbin into the shuttle will cause the depleted bobbin 5 to be ejected from the shuttle.

Slight changes might be made in the details of construction of my invention without departing from the spirit thereof or lim-

iting its scope, and hence I do not wish to restrict myself to the precise details herein set forth.

Having fully described my invention what 5 I claim as new and desire to secure by Letters-Patent, is:—

1. In transfer means for filling replenishing looms, the combination with a bobbin carrier, of transfer devices comprising a 10 movable arm having a head at one end, a rod removably and adjustably secured at one end to said arm, a finger carried by said removable rod and adapted to engage the filled bobbin between its ends and a spring 15 connected with said arm and operating normally to maintain said head and finger out of engagement with the filled bobbin.

2. In transfer means for filling replenishing looms, the combination with a bobbin 20 carrier, of transfer devices comprising a movable arm having a head at its free end to engage an end portion of a filled bobbin, a threaded rod projecting laterally from

said arm, and a finger adjustable on said rod and disposed to engage a filled bobbin 25 in the carrier between and removed appreciable distances from both ends of said bobbin.

3. In transfer means for filling replenishing looms, the combination with a bobbin carrier, of transfer devices comprising a movable arm having a head and a boss at one end, a laterally projecting threaded rod entering said boss and detachably secured to the latter, an elongated finger to engage an intermediate portion of a filled bobbin, said finger having a shank mounted on said threaded rod, and nuts on said rod to retain the finger at any desired adjustment. 30

In testimony whereof, I have signed this 35 specification in the presence of two subscribing witnesses.

CLAUDE T. WOMACK.
